UNITED STATES PATENT OFFICE.

ISADORE BLUMENTHAL, OF NEW YORK, N. Y.

DESIGN FOR AN ASH-TRAY AND CIGAR-CUTTER.

52,264.

Specification for Design.

Patented Aug. 20, 1918.

Application filed April 2, 1918. Serial No. 226,314. Term of patent 14 years.

To all whom it may concern:

Be it known that I, ISADORE BLUMENTHAL, a citizen of the United States, residing at the city of New York, borough of Manhattan, in the county and State of New York, have invented a new, original and ornamental Design for an Ash-Tray and Cigar-Cutter, of which the following is a specification, reference being had to the accompanying drawing, forming part thereof.

Fig. 2 is a side view of the ash tray and cigar cutter shown in Fig. 1.

Fig. 3 is a front view of the ash tray and cigar cutter shown in Fig. 1.

I claim:

The ornamental design for an ash tray and cigar cutter as shown.

ISADORE BLUMENTHAL.
